PULP BEATING ENGINE

George W. Dodge, Greenwich, Conn., assignor to
 Paper and Industrial Appliances, Inc., New
 York, N. Y., a corporation of New York

Application October 21, 1941, Serial No. 415,932

8 Claims. (Cl. 92—24)

This invention relates to the production of pulp from cellulosic material, and more particularly it relates to treatment steps and apparatus having to do with the more specific conditioning or refining of the pulp stock before it is dewatered and made into the final sheet product on paper machines. This includes defibration of the cellulosic material and hydration of the separated fibers. The degree of intermeshing of the fibers of an otherwise desirable pulp, determines generally the character, grade and mechanical strength of the final paper product.

According to a more specific concept, this invention relates to improvements in pulp beating engines or refiners of the "stone roll" type in which the conditioning and refining of the pulp fibers is effected. A beater or refiner of the general type contemplated herein comprises usually a tank having a beater roll coacting with a stationary member or bed-plate, the curvature of the bed-plate substantially corresponding to the curvature of the beater roll having therebetween a clearance through which the pulp is impelled by rotation of the roll, while parting of the fibers caused by the working faces of the beater roll and the bed-plate respectively, conditions the fibers for whatever grade or type or strength of final product is desired. In a beater of this type, the stock enters at one side of the beater roll and, due to the rotation of the roll, is forced under the roll and through the treatment zone between the rotary and stationary attrition faces from whence it is projected or thrown upwardly from the other side of the roll. After such treatment, the pulp is ready for further treatment in various ways.

For a better understanding of certain features of the invention, reference may here be had to a special type of refining effect, namely, the effect of the pulp fibers in the defibrated pulp being additionally roughened up in a manner to enable them to intermesh or felt more firmly with each other so as to provide greater mechanical strength in the final product. This phenomenon, which comprises putting whiskers on individual fibers, is sometimes called hydration. This effect is incident to such an additional refining step as will be discussed hereinafter in connection with this invention.

A more recent method, as disclosed in United States Patents Nos. 2,008,892 and 2,145,851 to Asplund, differs from the older conventional digesting or cooking steps in that the preliminary softening of the lignin of the wood chips or lignocellulose material, as well as subsequent mechani-

cal defibration take place at elevated steam temperatures and elevated pressures under conditions of non-submergence of the material being treated.

As a matter of environment, the beater considered to embody features of the present invention may operate as a refiner in any of these or similar processes. Yet it may also perform a more specific function, namely, when used in a supplemental refining or attrition step, whose purpose is fiber separation following the usual Asplund combination of defibrator and refiner, called herein secondary refining or hydration. It is called secondary since it can follow the ordinary defibration and refining station which correspondingly might herein be called the primary or pre-refining step. By the special treatment received in the secondary refining step or station, the fibers which are relatively smooth and non-coherent when they emerge from the primary refining treatment, are roughened up, without necessarily being shortened, in a manner whereby whiskers or branch fibrillae are effected on them. When in a mass of fiber, branch fibrillae of one fiber become enmeshed with those of another, and thus form a fairly interlocked, felted, or coherent fibrous system, which makes for surprisingly greater mechanical strength in the final product. The specific roughening effect upon the fibers in the secondary refining or hydration step may be attained when basalt lava insets are used to furnish abrasion or attrition faces on the beater roll as well as on the bed-plate.

Improvements according to the present invention are realized when made upon a type of refiner in which the beater roll is only partially submerged in the stock of the tank.

It is among the objects of this invention to provide a beater engine or refiner which is simple and compact of construction, and yet flexible in operation. By flexibility of operation is meant that the machine is capable of handling a relatively wide range of pulp densities and viscosities, for whatever length of effective treatment is desirable for the stock during its one passage through the machine.

Hence, a more specific object is to provide means whereby the spiraled movement of the stock around the beater roll and through the apparatus can be readily and accurately controlled in the sense that control may be exercised as to the number of turns of the spiral path to be followed by the stock, for thereby controlling the total length of that path for any particular type

of pulp. In other words, the total amount of abrading or roughening treatment to be given the pulp during one passage through the refiner casing.

Another object is that the operation should be stable in view of the fact that many stocks have the tendency to segregate before or at the entrance to the beater roll, with the result that only segregating thin stock is treated in the beater while fibers are detained, thus giving rise to congestion and unstable operation of the machine. Still another object is to produce an improved beater or refiner which is flexible and stable in operation, and furthermore economical in power consumption.

Certain of the above objects of this invention are attained by causing the beater roll to project the stock pulp into the space above the beater roll and along a suitable curvature of the hood that forms the top portion of the casing surrounding the beater roll. By correlating the curvature with the velocity of the stock, the projected particles following this curvature are guided back to the feeding side of the beater roll in the form of a flow stream representing a substantially undispersed mass of projected pulp impinging upon the pulp bath and having kinetic energy adapted to agitate it.

Objects are further attained through the discovery according to this invention that the degree of spiralization in the movement of the stock around the beater roll that is the number of turns of the flow path per unit of length of beater roll, is in effect not dependent upon or controllable by baffle arrangements, but is controllable and in fact adjustable by a coordination of the speed of rotation of the beater roll to the rate of feed and withdrawal of stock from a covered trough that is internally substantially free of obstructions or baffles, and in which the beater roll is partially submerged. In other words, the variable relationship whereby the flow conditions can be controlled, is the relation between the rate of speed of the beater roll and the hydraulic head of a sloping feed pulp stock level along the beater roll in the tank. The slope of the stock level extends from the inlet end to the outlet end of the tank, and the degree of slope is due to and depends upon the character and the internal friction of the stock, as well as the general rate of flow at which the stock is passed through the tank.

As a consequence of this discovery the invention is embodied in a beater construction in which a beater roll is partially submerged in a covered tank or trough, and the tank is so specially shaped with respect to the roll, that by the rotation of the roll, stock is drawn in under the roll and forced between the roll and the bed-plate or bed-plates, to be impelled or projected around and above the roll in a manner to cause it to be guided in a trajectory-like path until it falls on the stock bath that extends along the inlet side of the roll. The resulting spiralized movement of the stock around the beater roll is the resultant of two speed components, namely, of one component represented by the speed of the beater roll, and another component represented by the rate of flow of stock through the tank from the inlet to the outlet end thereof. The degree of spiralization in the movement of the stock around the beater roll thus becomes a function of the flow volume that is sent in the general direction from end to end through the tank, and that flow volume is adjustable. The

spiralized movement of the stock can be rendered uniform to the extent that the machine as a whole is properly designed and proportioned, and to the extent that the slope or hydraulic head of the stock level is allowed to develop and to remain free from any substantial disturbance.

It is therefore one of the features of this invention to provide an outlet in the form of adjustable interceptor means whereby pulp can be withdrawn at a desired rate at the outlet end of the tank. The word interceptor is chosen because it designates the feature that the falling pulp to be withdrawn at the outlet end of the tank is not allowed to reach the body of the pulp stock in the tank, but is intercepted in its fall as by an adjustable splitter or doctor. By intercepting an adjustable quantity of outgoing or finished pulp in this manner, it is intended to preserve more desirably uniform flow conditions in the stock body in the machine than would be obtainable by drawing the effluent directly from the stock body.

According to another feature, feed enters the stock bath about the middle of the inlet side of the beater roll, while outlet means are provided at each end. With this arrangement the stock level develops a peak or maximum hydraulic head about the middle and slopes off towards each end or outlet. Hence the amount of hydraulic head or slope of stock level required for operation is reduced, so that even a rather viscous stock can be treated at relatively low submergence of the beater roll and hence at a saving in power. This reduction in the amount of roll submergence lowers the power requirements, releasing a larger proportion of the connected power for the purpose of useful stock treatment, and increases the mechanical efficiency of the machine.

Another feature has to do with the design and special contour of the trough or chamber in its relation to the general contour of the beater roll. The contour of the chamber is to be such as to provide a smoothly converging passage for the stock toward the inrunning nip formed by the roll surface. In other words, there is produced what might be called a horn-shaped angle between the two curved surfaces, of which the beater roll is one and the other is the correspondingly curved section of the tank bottom. The contours of this angle or approach should be of such coacting curvature that reflecting forces exerted by the tank bottom upon the stock due to the rotation of the beater roll, will work for a continuity of flow in the direction of rotation of the beater roll, irrespective of the density of the stock. That is to say, according to this feature, a carefully designed contour of the tank bottom that resembles a convolute curve and that smoothly converges towards the circumference of the beater roll, will eliminate a tendency for the stock to segregate into water and solids, a phenomenon which is often responsible for unstable operation and congestion in the machine. To illustrate this point, many machines of this general character appear to be handling a stock of high density, whereas they are actually handling and treating a particular portion thereof at a lower density of stock which is in a more fluid state, while the differential volume of higher density stock which, in combination with this lower density stock, would equal the assumed quantity of higher density stock, passes through ineffective passageways and recombines with the treated low density stock, and is thus discharged from the machine without having been sufficiently treated. However, the sides of the horn

angle have such relation to each other that the component of the parallelogram of the forces acting therein is inward toward the stock nipping end of the horn. An impelling force is supplementally applied to stock particles in this direction by the cavities or grooves or lights in the attriting insets on the beater roll, since they extend substantially longitudinal of the roll or at right angles to the direction of pulp or stock propulsion into the nipping end of the horn angle.

A further feature relating to the horn angle resides in a variation of the angle thereof for a purpose presently to be explained: The stock is most dense when it is emitted from the feed pipe into the stock chest of the beater and least dense where the stock or pulp exits from the beater. This change is only apparent rather than real, for the actual moisture content is not changed. The beating with its consequent hydration causes the stock to have progressively increased fluidity. Taking this fact into consideration, this invention contemplates pinching-in the walls of the stock basin or tub toward the end of the beater roll. That is, the distance between the tub wall and the feed side of the roll is greater in the region of the stock feed to the roll than is the space between the tub wall and the roll in the region of the stock exit from the beater. This in effect amounts to gradual slenderizing of the horn-angle as the pulp progresses from inlet to exit. This progressively decreasing stock flow-through space between tub wall and beater roll stock-receiving space progressively decreases in proportion as the stock being beaten has its fluidity progressively increased, whereby the stock will be discouraged from lessening its rate of spiralization around the roll or from unduly hastening its rate of progress toward the pulp outlet—in other words, to prevent harmful bypassing, and to maintain a desired period of active detention of the stock under treatment in the machine.

Mention has been made above that the stock impelled or projected from the roll as it passes from between the roll and bed-plate is guided in a trajectory-like path. This is an important feature and is accomplished by means of a hood or cover that may be said to form the top of the casing that houses the roll and bed-plates. This hood is so designed as to have a contour such that it forms a tangent or tangential curve with that point of the roll from which the stock leaves the roll and bed-plate. The idea is that the outgoing or projected stock does not break its stream flow but is guided in a curved path by the hood until the guided stock reaches a point from which it can fall substantially vertically. The projected stream of stock particles have kinetic energy acquired due to the circular motion of the roll cavities moving the stock from the bath under the roll to the point of projection. It is desired to conserve this energy rather than let it be dispersed. To that end the curvature of the inside or stock side of the hood is so curved that centrifugal force tends to hold the impelled stock particles upwardly against the hood so that the hood causes moving stock particles to have their direction changed until they reach the vertical pulp feeding side of the roll but that when they reach the vertical and fall, the stock particles still have residual kinetic energy sufficient to effect some agitation or turbulence in the stock bath as they enter it. Thus, this invention teaches the importance of having all forces acting through

the stock particles to be expended in a direction toward the roll and finally in the bath instead of being exerted against the tub wall, for when exerted against the tub wall, this causes segregation of the stock and water with a consequent plugging of the flow of stock from the bath to the roll.

To this end, the flow of stock particles as they are projected from between the roll and the bed-plate, must leave the roll at as near a tangent as possible and in a stream-flow sheet unmolested by eddies or other disturbing influences, such as offsets, walls, or back-drop spaces. It is also undesirable that any substantial quantity of the projected stock particles leave the stream-flow sheet that is being guided by the hood and fall as rain or snow. It is desired to keep the particles in a flowing stream or sheet of stock that follows the underside of the hood until the vertical is reached, and to minimize the separation or segregation of individual particles from that stream or sheet. The object is to cause each particle to conserve its kinetic energy as far as possible to be expended in agitating the stock bath when the particle reaches it, to which end the curving of the projected stock particles is done as a result of centrifugal force rather than by the expenditure of kinetic energy. This feature is important of itself but it is also important since the particular manner of feeding the stock from the bath to the roll is made highly effective by the combined and conjoint action therewith of the energy conserving treatment of the projected stock.

It is believed that it is this combined action that enables a machine that embodies the teachings of this invention to treat relatively high density free stocks up to 10% density, without experiencing difficulties due to segregation of water and fiber that are the usual cause of plugging of the feed passages leading to the roll, and interruption of operation. The roll rotating at sufficient speed centrifugal force causes the projected stock to move in the form of a more or less solid sheet or undispersed mass along the curved path defined by the hood, and kinetic energy thus conserved in the mass of the projected stock adds to the force of gravity, as the stock impinges downwardly upon the pulp bath along the outer side of the receiving space of the pulp bath. When re-entering the pulp bath in this manner the energy of the projected pulp will counteract or compensate for adverse tendency of the roll to segregate fibers from a free flowing high density stock, whereby fibers are adapted to be deposited against the front wall of the casing with resultant plugging and congestion in the pulp receiving space.

Other features of the invention have to do with that type of roll beater wherein the beater roll is said to be floatingly supported with respect to the bed-plates so that as more or less stock tends to pass between the roll and bed-plates, the axle of the roll automatically raises and lowers to provide respectively more or less space between it and the fixed bed-plates. Another feature of this invention is the provision of weight and counter-weight arrangements whereby this automatic tolerance capability of the roll can be nicely adjusted, especially as to the limits of its tolerant positions. According to this feature, therefore, the relative contours of the horn angle as represented by the two converging curved surfaces should be more or less a function of roll speed, distance of

stock travel, and rate of stock flow, for efficient performance in the above respects.

Other features relate to structural details in the mounting of the basalt lava insets.

It is a fact that some pulps, for instance, pulp made from waste paper stock, that has been well hydrated usually have their drainage or free flowing characteristic slowed down, that is to say, the rate at which water leaves the pulp becomes less and less each time that it is repulped. Such a pulp is therefore difficult to handle on the paper machines. Additional and possibly excessive dilution of the stock is sometimes resorted to in order to overcome this difficulty, although it also places a corresponding load upon the paper machine where the sheet of pulp must be dewatered.

Another difficulty lies in the handling of free flowing or quick draining stock of high density, because such a stock tends to segregate when treated in a beater of known type. This difficulty also has been considered remediable to a degree only by means of dilution of the stock being fed to the beater.

In view of these difficulties due to characteristics of the stock, it is another object of the invention to reduce the load on the paper machines by producing a pulp that is free flowing and well defibrated, well hydrated, and at the same time of relatively high density.

The invention possesses other objects and features of advantage, some of which with the foregoing will be set forth in the following description. In the following description and in the claims, parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

Fig. 1 is a side view of a pulp conditioning apparatus embodying the invention and showing adjusting mechanism for the yieldably mounted beater roll.

Fig. 2 is a top view of the apparatus.

Fig. 3 is a cross-section through the apparatus, taken along the line 3—3 in Figs. 2 and 4, and showing more clearly the casing construction to comprise a lower or base portion in which the beater roll operates, and cover portion extending from front to rear of the base portion and constituting therewith a specially shaped pulp receiving space at the feeding side of the beater roll.

Fig. 4 is a detail plan view in reduced scale of a portion of the base per se of the casing construction, which embodies a characteristic novel configuration of the pulp receiving space widening in the middle and narrowing towards each end.

Figs. 5 and 6 represent cross-sections taken upon Fig. 4 on the lines 5—5 and 6—6 respectively, showing various degrees of narrowing of the pulp receiving space and of the horn angle.

Fig. 7 is an enlarged detail cross-section of the means for fastening basalt insets on the beater roll.

Fig. 8 is a part sectional plan view of the fastening means shown in Fig. 7.

Fig. 9 is a sectional perspective view of the fastening means shown in Figs. 7 and 8, with a basalt inset about to be positioned upon the beater roll.

The pulp conditioning apparatus embodying this invention comprises a beater roll 10 having trunnions 11 and 12 mounted in bearings 13 and 14. Each of the bearings 13 and 14 has identical yieldably mounted supporting means disposed at each end of the apparatus so that only one of them need be described in detail. These yieldably mounted supporting means comprise a bell crank lever 15 which in turn is fulcrumed upon a fixed bearing 16. The bell crank lever 15 has a horizontally extending arm 17 and an upwardly extending arm 18 which latter in effect comprises the trunnion bearing 13. A compound system of weighted levers imparts adjustable upward pressure to the horizontal arm 17 of the bell crank lever, whereby the beater roll 10 is held against a set of stationary bed-plates 19, 20, 21 which in effect form a part of a casing construction that surrounds the beater roll 10 and is designated collectively by the numeral 22, the trunnion bearings 13 and 14 and their yieldably mounted supporting means being disposed outside of this casing construction at the respective ends thereof.

The casing construction 22 is shown to comprise a concrete base or portion 23 forming the lower troughlike section of the casing and forming with the beater roll 10 a space in the form of a horn angle that constitutes a part of a pulp receiving space 24 at the feeding side of the beater roll 10 to which rotation is normally imparted in the direction of arrow 25 as by a drive pulley 25^a carried by the free end of the trunnion 11.

A rear wall portion of the casing construction 22 closely follows the contour of the beater roll 10, for, together with the beater roll, the rear wall portion forms the active or pulp conditioning part of the apparatus, whereby the desired conditioning of the stock fibers or creation of the desired branch fibrillae on the stock main fibers is effected. This rear wall portion is herein identified collectively by its height R, although it is shown to comprise more or less familiar structural sections, namely, boxlike castings or sections 26, 27, 28 for holding the above mentioned exchangeable bed-plates 19, 20, 21. The bed-plates may be of the same material, namely, basalt, as corresponding basalt insets usually provided upon the beater roll and forming the pulp treating surfaces thereon. The boxlike sections 26, 27, 28 may be bolted together in some suitable manner not particularly shown and they are backed up by corner posts 30 and 31 anchored in some suitable manner upon the base.

A detail plan view of the lower portion of the casing construction or concrete base 23 is shown in Fig. 4 to have at the ends thereof horizontal faces 23^a and 23^b respectively terminating in rearwardly extending protrusions or protruding portions 23^c and 23^d, for sustaining and mounting thereon portions of the end and rear wall constructions of the casing 22. In this way the corner posts 30 and 31 are anchored upon the extreme end of the rearward protrusions 23^c and 23^d.

At the front or feeding side of the beater roll 10 the base 23 is formed with a chamber 23^e for

receiving treated pulp discharged from the apparatus in a manner hereinafter to be described, and provided with a treated pulp outlet connection 23^c.

The inner face of the base 23 is furthermore shaped in such a manner that the horn angle which it forms with the beater roll 10 is widest at the middle of the base, but narrows down gradually towards the ends thereof. This configuration is perhaps best illustrated by taking suitable cross-sections of the base, such as shown in Figs. 5 and 6. Thus the section in Fig. 5 being the closer one to the middle of the base, shows a wider horn angle, while the section according to Fig. 6, being taken closer to one end of the base, shows a narrow horn angle. It will thus be understood (see Fig. 4) that a portion *a* of the base 23 has a horn angle of constant and maximum width, while the adjoining respective end portions *b* and *c* have a horn angle the width of which decreases gradually from the maximum to a minimum at the end of the base 23. For reasons and purposes hereinafter to be explained, this gradual variation of the horn angle presents a configuration of the feed receiving space that offers a gradually increasing impediment to the flow, of stock or pulp passing from a wider to a narrow cross-section or horn angle.

The casing construction 22 further comprises a front wall 32 identified by its height *F*, and being provided at each end with an adjustable pulp discharge device 33 and 34 respectively. This device comprises a doctor 35 that is adjustable about the horizontal axis of a pivot connection 36 whereby it is mounted outside the casing upon the concrete base 23. The doctor 35 has lateral wall portions 35^a and 35^b fixed thereto so as to form a chute that extends through an opening in the front wall portion 32 and is adjustable between and with respect to stationary plates 32^a and 32^b as indicated by slots 32^c therein and by wing nuts 32^d and 32^e. The doctor 35 is adapted to intercept a desired flow volume of treated pulp that is projected by the beater roll 10 into the pulp-receiving space 24, and to discharge it from the interior of the casing into the chamber 23^e for further disposal. A specially shaped cover portion 37 forms the top of the casing, as it arches from the rear wall portion *R* to the front wall portion of *F*. The cover portion 37 comprises the arched body portion 37^a and vertical end portions 37^b and 37^c respectively. Correspondingly the lower or body portion of the casing construction comprises end wall portions 37^d and 37^e respectively, which in turn may be constructed in sections such as indicated in Fig. 1, and they are supported and mounted upon the horizontal faces 23^a and 23^b of the concrete base shown in the Fig. 4. Trunnions 11 and 12 of the beater roll, of course, extend through the end wall portions 37^e and 37^d respectively being sealed therein in some suitable manner. By way of a connecting wall portion 38 the cover portion 37 blends tangentially into the rear wall portion *R*, with the result that if an adequate rate of rotation is applied to the beater roll 10, it will project the pulp into the pulp-receiving space 24 substantially as shown in Fig. 3. That is to say, the centrifugal force set up in the projected mass due to the curvature of the cover portion 37 will cause a major portion of the projected pulp to move in a form of a compact stream or sheet along the interior face of the cover portion. With the energy of its momentum thus preserved, this mass or moving sheet of pulp following downwardly the contour of the front wall portion 32 impinges

upon the outer edge portion of a body of pulp 39 that is maintained in the pulp-receiving space, and thereby causes a certain type of effective agitation in the pulp body.

5 An inlet 40 for feeding stock to the interior of the casing is shown to be provided on the cover portion 37 at the middle thereof, that is to say intermediate the two discharge devices 33 and 34. In this way, half of the incoming stock 10 moves in one direction, namely, towards the discharge device 33 while the other half moves in the opposite direction, namely, towards the other discharge device 34, whereby the stock is caused to progress in a spiral movement around the beater roll gradually from the inlet to the respective outlet and in a controlled manner hereinafter fully to be described.

15 The stock is projected against a lining 41 that covers the inside of the arched body portion 37^a of the casing cover 37.

20 Initially in this detailed description it was said that a compound system of weighted levers imparts adjustable upward pressure to the horizontal arm 17 of the bell crank lever 15, whereby the beater roll 10 is held against the stationary bed-plates 19, 20, 21, and that the trunnion bearings 13 and 14 and their yieldably mounted supporting means are disposed outside of this casing construction, namely, at the respective ends thereof. The detailed description of the 25 casing having been completed as above, there will now be given the detailed description of the compound lever system that is adapted to cause the beater roll 10 to yieldably engage the bed- 30 plates 19, 20, 21 with an adjusted amount of pressure and thereby to provide for the stock 35 the desired kind of attrition treatment.

According to Fig. 1, the horizontal arm 17 of the bell crank lever 15 rests upon a fulcrum 40 portion 42 which in turn constitutes a part of the short arm 43 of a double armed or primary lever 45 having a long arm 44 opposite the short arm 43. A fulcrum point 45^a upon a bracket or support 45^b sustains the primary lever 45. The 45 end of the long arm 44 is loaded with a primary weight 46 pressing the fulcrum portion 42 and thereby the arm 17 of the bell crank lever 15 upwardly, thus urging the beater roll against the bed-plates 19, 20, 21. A fine adjustment of 50 this pressure due to the leverage of weight 46 is provided by way of a smaller or secondary shiftable weight 47 that loads the long arm 48 of a double armed or secondary lever 50 having as an opposite arm a short arm 49. A fulcrum 55 point 50^a upon a fixed bracket or support 50^b sustains the secondary lever 50. The short arm 49 is linked by a connection or reach rod 51 to the short arm 43 of the primary lever 45. It will be noted that the lower end of the reach rod 51 is connected as at 52 to the very end portion of the short arm 43, whereas the upper end of the 50 reach rod 51 is connected to the short arm 49 at a point 53 that is nearer to the fulcrum point 50^a of the secondary lever than to the outer end 55 of the short arm 49 of that lever. A threaded spindle 54 paralleling the secondary lever 50 is rotatably mounted thereon and operable by a hand-wheel 55 and through a set of bevel gears 56 and 57 mounted upon the extreme end of the 60 short arm 49 of the secondary lever 50. The spindle 54 has threading engagement with the secondary weight 47, so that rotation of the hand-wheel 55 may cause the weight 47 to shift or ride along the secondary lever 50 to any point between the extreme ends thereof. It will thus

be noted that, depending upon the adjusted position of the shiftable weight 47 on secondary lever 50, effective leverage may be added to or subtracted from the leverage effect which is due to the primary weight 46. An identical compound lever system such as just described is provided at each end of the machine (see Fig. 2) for each respective end of the beater roll 10, and it is desirable that a single manipulation should actuate both in unison. Therefore, the hand-wheel 55 at one end of the machine is rigidly connected with a similar hand-wheel 55^a at the other end of the machine through a shaft 58 that extends parallel to the axis of the beater roll. By turning either one or the other of these hand-wheels 55 and 55^a, the secondary weights 47 and 47^a respectively at opposite ends of the machine can be moved in unison.

There is further shown (see Fig. 3) a releasing mechanism M whereby the operating pressure of the beater roll 10 against the bed-plates 19, 20, 21 can be adjusted or entirely released. It comprises a worm drive 59 having a worm gear 60 and a worm 61. This worm drive is shown to be mounted against the underside of the fixed bracket or support 50^b. The worm 61 has a worm shaft 62 rotatable by a set of bevel gears 63 (only partly visible in Fig. 3) which are supported by a bracket 64 mounted upon the adjoining end wall of the casing construction. A hand-wheel 65 may be rotated to turn the worm gear 60 through the level gears 63, the worm shaft 62 and the worm 61, so as to impart axial movement to a screw or short threaded spindle 66 whose lower end engages upon the horizontal arm 17 of bell crank lever 15 and depresses the same when the rotation of the hand-wheel 65 moves the screw 66 downwardly against the combined leverage effect of both the primary weights 46 and 46^a and the secondary weights 47 and 47^a, thereby adjusting or releasing the pressure that normally urges the beater roll 10 against the bed-plates 19, 20, 21. Since two such releasing mechanisms M and M' are symmetrically arranged, one at each end of the machine, it is desired that both be actuated in unison. Therefore the rotation of a hand-wheel 65 at one end, or a similar hand-wheel 65^a at the other end of the machine, both interconnected by a shaft 68, will work both releasing mechanisms M and M' simultaneously and in unison.

Features of this invention relating to the construction of the beater roll per se and more specifically residing in the manner of mounting and fastening attrition elements such as basalt lava blocks on the beater roll 10, are illustrated in Figs. 7, 8, 9. A hollow body or drum or casting 69 has provided on it radial ribs 70 which form with one another receiving spaces for the attrition elements to be assembled upon the roll. The drum 69 may be a casting in which the foot portions of the ribs are embedded. Each rib 70 comprises a straight radially extending body portion defined by parallel side surfaces and terminating in a flaring top portion 70^b defined by beveled faces 70^c and 70^d and by a flat top face 70^e. The attrition elements to be assembled upon the roll are designated by the numeral 71 and they may be in the form of specially shaped basalt lava blocks or units suited to be placed into and retained in the spaces between the ribs 70. Because of the heavy stress placed upon them due to centrifugal and other forces, the attrition elements 71 are herein disclosed as being securely retained or anchored upon the roll by means of turnable

latch members 72 mounted as by bolts 72^a on the top face 70^e of the flaring end portion 70^b of the ribs 70. Grouting 73 or the like fills the seating clearances around the blocks, some grouting or the like covering as at 73^a the top face of the ribs and the latch members 72 thereon so as to form a smooth groove or pocket 73^b. An attrition element 71 such as herein shown is an elongated block of basalt lava having a beveled shoulder 74 and 74^a respectively on each side, which shoulders correspond to and are to be retained by beveled faces 70^c and 70^d respectively of the flaring top portion 70^b of the ribs.

Prior to the insertion of the block 71 which may be introduced longitudinally into the spaces between the ribs, the latch members 72 are turned to a position shown in Fig. 9 where they line up or co-extend longitudinally with the ribs 70. After a block 71 has been inserted and positioned, the corresponding latch members 72 are then turned to the position shown in Figs. 7 and 8, where they extend transversely of the ribs and engage in recesses 76 that are correspondingly provided in the sides of the blocks 71, and are tightened in this position by the bolts 72^a. With proper arrangement of the latch members 72 on the ribs and the corresponding recesses 76 on the blocks, the blocks can be positioned as well as anchored in a positive and predetermined manner and with a predetermined uniformity. The blocks 71 are shown to have provided in the top portion thereof a longitudinally running groove or pocket 77, so that in a beater roll on which all blocks 71 have been properly assembled deeper pockets 73^a will be found to alternate with shallower or smaller pockets 77, which pockets serve to trap corresponding volumes of stock under treatment in the machine, permitting the beater roll 10 to carry the material from the pulp receiving space 24 past the bed-plates 19, 20, 21, and to project it again back into the pulp receiving space 24 in the particular manner substantially as illustrated in Fig. 3.

The operation of the apparatus is as follows: Stock to enter the machine for treatment is fed at a desired rate through the inlet 40 into the interior of the casing 22 and more particularly into the feed receiving space 24 where it enters the body of pulp 39 in the casing substantially at the middle thereof. The pulp discharge or interceptor devices 33 and 34, if the doctor blade thereof is properly adjusted, cause the withdrawal of an equal amount of treated pulp from each end of the casing. Consequently there is a tendency of the pulp in the body 39 to flow from the point of feed towards each end of the casing, the level of the pulp, because of the viscosity thereof, forming a corresponding slope from the center to each end of the pulp bath in the feed receiving space 24.

The beater roll 10 is driven so as to acquire a high enough speed component whereby the pulp is caused to progress in opposite spiralized paths around the beater roll from the central inlet to each outlet. Because of the construction of the feeding space and other factors that influence the operation of this machine, these spiralized paths of the pulp under treatment will establish themselves in a desired manner as a matter of operating equilibrium and without any interference by interposed structures. In fact, the desired motion of the pulp as established in this machine might be considered as the resultant of, or as being in varying degrees dependent upon the following co-acting factors: namely, the rate

of stock feed and of treated stock withdrawal, the rate of rotation of the beater roll, the consistency and characteristics of the stock under treatment, the degree of pressure of the roll against the bed-plates 19, 20, 21, and the structural configuration of the feed receiving space 24 including the top portion of the casing in co-relation to the size and speed of the beater roll.

In order to achieve the desired efficiency in the treatment of the pulp, all the material under treatment should move along the aforementioned spiral paths with substantial uniformity from inlet to outlet while short circuiting of the material is avoided. As the hydration of the stock proceeds in the course of its spiralized path, there is the tendency for the fluidity of the stock to increase, causing an increase in the horizontal flow speed component in the pulp body 39. The change of fluidity thus tends to upset or impair the regularity, uniformity and efficiency of the intended spiral paths because of possible short circuiting or because of a treatment burden that is unevenly distributed over the entire length of the beater roll. However, the lowering of operating efficiency due to change in fluidity is compensated for by the gradual narrowing down of the feed receiving space as regards the horn angle portion thereof. That is to say, the resistance to the horizontal flow speed component of the pulp body 39 is increased as its fluidity is decreased.

In pulp conditioning machines of this general class using a beater roll, there is the ever present problem of the stock fibers segregating at the pulp receiving side of the beater roll, especially when handling high density free flowing stock. Again, this is compensated for in the operation of the present improved machine by a functional co-ordination of the size and speed of the beater roll with the shape and configuration of the surrounding casing construction. That is to say, at a proper speed of rotation the longitudinal grooves or pockets provided over the roll circumference will seize the stock from the pulp receiving side, force it past the bed-plates 19, 20, 21 for defibration and hydration treatment, and release it tangentially with sufficient momentum to carry it substantially undispersed away from the roll. Because of the centrifugal force acting upon the projected mass, the projected pulp will move in a substantially compact stream or sheet along the curved or concave guide face that is presented by the interior face of the top portion of the casing. The operation indeed should be such that the centrifugal force due to the momentum carries the material substantially undispersed and with a mass impact to the outer longitudinal zone of the pulp body 39, whereby there is constantly induced in the pulp body 39 a type of positive agitation which I have found to be capable of preventing the troublesome segregation of the pulp and consequent congestion. The stream or sheet of material projected in this special manner is designated by the numeral 79 in Fig. 3 incidentally showing only minor portions of stray material deviating from the trajectory as defined by the top portion of the casing.

I claim:

1. A stock conditioning apparatus comprising a closed casing having ends and a concave bottom section as well as a substantially concave top section, a horizontally extending cylindrical

beater roll rotatably mounted within the casing disposed to be substantially tangential to one side of the concave bottom section to form with the bottom section a stock-receiving space having a horn angle leading to the place of tangency of the roll and the bottom section, bed plates for the bottom section adjacent the place of tangency, inlet means for continually feeding stock to the stock-receiving space and into the horn angle, the concave top section forming a trajectory path for stock projected upwardly by rotation of the roll to guide such stock to return to the stock-receiving space and back into the horn angle, means for rotating the roll at a speed sufficient to project such stock in its trajectory path, whereby said stock is guided into the outer marginal zone of said stock receiving space, and treated stock outlet means adapted for discharging stock at the rate at which stock is fed and horizontally spaced from the stock feeding inlet means whereby a hydrostatic head is maintained between the inlet and outlet for flowing stock from inlet toward outlet at a speed controlled by the rate of feed while rotation of the roll acting on such flowing stock carries stock along a spiralized path around the roll from inlet to outlet.

2. Apparatus according to claim 1, in which said outlet means comprise an adjustable doctor effective to intercept a portion of the projected stock on its return path.

3. Apparatus according to claim 1, in which the inlet is disposed intermediate the ends of the casing, and in which said inlet means comprise an outlet at each end of the casing.

4. Apparatus according to claim 1, in which the inlet is disposed intermediate the ends of the casing, and in which said outlet means comprise an outlet at each end of the casing and an adjustable doctor for each outlet and effective to intercept respective portions of the projected stock on its return path.

5. Apparatus according to claim 1, in which the stock receiving space is increasingly restricted from said stock inlet means toward said pulp outlet means in a manner that the area represented by said horn angle becomes increasingly narrower thus presenting to the stock a continuously decreasing flow area as the stock proceeds along said spiralized path.

6. Apparatus according to claim 1, in which the inlet is disposed intermediate the ends of the casing and in which said outlet means comprise an outlet at each end of the casing, and the stock receiving space is increasingly restricted from the inlet toward each outlet in a manner that the area represented by said horn angle becomes increasingly narrower thus presenting to the stock a continuously decreasing flow area as the stock proceeds along said spiralized path.

7. Pulp stock treating apparatus according to claim 1, in which said return path comprises a substantially vertical portion substantially immediately above the said body of stock.

8. Pulp stock treating apparatus according to claim 1, in which the inlet is disposed intermediate the ends of the casing, in which said outlet means comprise an outlet at each end of the casing and an adjustable doctor for each outlet and effective to intercept respective portions of the projected stock on its return path.

GEORGE W. DODGE.
